(No Model.)

H. BAETZ.
AIR HEATING APPARATUS.

No. 604,013.

Patented May 17, 1898.

Fig. 1.

UNITED STATES PATENT OFFICE.

HENRY BAETZ, OF ST. LOUIS, MISSOURI.

AIR-HEATING APPARATUS.

SPECIFICATION forming part of Letters Patent No. 604,013, dated May 17, 1898.

Application filed June 26, 1897. Serial No. 642,455. (No model.)

To all whom it may concern:

Be it known that I, HENRY BAETZ, a citizen of the United States, residing at St. Louis, in the State of Missouri, have invented certain new and useful Improvements in Air-Heating Apparatus, of which the following is a full, clear, and exact description, reference being had to the accompanying drawings, forming a part thereof.

10 My invention has relation to improvements in air-heating apparatus; and it consists in the novel arrangement and combination of parts more fully set forth in the specification and pointed out in the claims.

15 In the drawings, Figure 1 is a perspective view of the furnace, with part broken away to show the disposition of the steam-coils. Fig. 2 is a top plan view of the coils, and Fig. 3 is an end elevation of the upper portion of 20 the coils.

25 The object of my invention is to construct a steam-heated air-heating apparatus which, while it is compact, shall at the same time present a maximum amount of heating-surface to the incoming currents of air driven against such surface.

30 A further object is to so locate the air-fans relatively to the steam-pipes traversing the furnace as to produce a better disposition of 30 the air-currents about the heated surfaces presented by the pipes.

35 A further object is to produce a furnace which shall be cheap to construct and one which can be readily taken apart for purposes of repairs.

In detail the invention may be described as follows:

Referring to the drawings, 1 represents a 40 casing rectangular in cross-section, the main steam-pipes 2, 3 being disposed along the upper portions of the inner surface of two adjacent walls, the said pipes communicating with a common coupling 4, with which the steam-supply pipe (not shown) directly communicates. Screwed directly into the peripheral wall of the pipe 2 are a series of pipe-sections 5, provided with right and left hand screw-threaded ends, one end being adapted to screw into the wall of the pipe 2 and the 45 opposite or farther end to simultaneously screw into or couple with one end of a large U-shaped coupling 6, whose opposite end is

secured to one end of a pipe-section 7, leading back toward the wall along which the pipe 2 is disposed and coupling with one end 55 of a smaller U-shaped coupling 8, from whose opposite end a second pipe-section 5, parallel to the first section 5, extends. This arrangement is repeated along the length of the pipe 2, so that there extends downwardly in vertical planes a series of resulting coils, each having a series of large U-shaped couplings at one end disposed adjacent to the inner surface of one wall of the furnace and a series of smaller U-shaped couplings at the opposite end and along the opposite wall of the furnace-casing, the last return-pipe section coupling to a drain-pipe 20, located at a suitable point below the pipe 2 and disposed along the same wall of the casing. The pipe 70 20 is provided with a series of L-shaped nipples 9. A similar series of coils extends from the pipe 3, the arrangement, however, being reversed to that just described—that is, the nipples 9 are carried by the pipe 3, from which 75 the coils extend downward—when the last pipe-section of the coil is screwed directly into the drain-pipe 21, disposed along the same wall with the pipe 3, the pipes 20 and 21 having a common exit 10. The two series 80 of coil systems thus formed intersect each other at right angles, each pair of pipe-sections coupled to the smaller U-shaped coupling being adapted to be inserted into the space formed between any pair coupled to 85 the ends of the large U-shaped coupling, and by simply unscrewing, for example, the pipe-section 5 connecting the pipe 2 with its U-shaped coupling at the farther end and detaching the last pipe-section 7 from the nipple 90 disposed along the upper peripheral surface of the lower drain-pipe 20 it is apparent that any one of the series of vertical coils of which the sections 5, &c., 7, &c., form a part can be withdrawn from the intersecting series 95 (after removal, of course, of the wall of the furnace-casing) whenever such removal is necessary for purposes of repairs.

By the present arrangement there is formed a network of coils, dividing the air driven in 100 from underneath into many currents, each serving to abstract the heat from the maximum amount of heating-surface thus presented. The coils may be supported in any

suitable manner within the furnace-casing. The air is drawn in through openings in two opposite walls of the casing below the pipes by fans of any approved construction, the 5 hot air being delivered from the exit-opening 12, as seen by the arrows.

Having described my invention, what I claim is—

1. In an air-heating apparatus, a suitable 10 casing, steam-pipes disposed along the inner surfaces of two adjacent or contiguous vertical walls thereof, drain-pipes located below the steam-pipes and disposed along the same contiguous surfaces or walls of the casing, a 15 series of coils leading from each steam-pipe to its corresponding drain-pipe or that disposed along the same wall, the one series intersecting the other at substantially the angle which the contiguous walls make with each 20 other, and a fan located below the coils and carried by the wall of the casing, substantially as set forth.
2. In an air-heating apparatus, a suitable 25 casing, steam-pipes disposed along the inner surface of two adjacent walls thereof, a coupling at the meeting ends of the pipes for connection with a suitable steam-supply pipe, a series of pipe-sections secured directly to the 30 peripheral wall of one of the pipes and leading to the opposite wall of the casing, a large U-shaped coupling at the farther end of each of said pipe-sections, a return-pipe section leading back to the wall along which the main pipe is disposed, a small U-shaped coupling 35 at the adjacent end of said return-pipe, a second pipe-section leading back to the opposite wall, and so on in repetition of the first arrangement whereby a series of coils disposed in vertical planes is formed, the last 40 pipe of each member of the series terminating in a nipple disposed along the upper peripheral surface of a common drain-pipe dis-

posed along the wall of the first or main pipe, a second series of coils intersecting the first series, said second series being similar to the 45 first but reversely disposed thereto, that is to say, the adjacent steam and drain pipes having the arrangement and disposition of nipple connections and U-shaped couplings 50 reversed, whereby the large U-shaped couplings of one series are disposed along a wall adjacent to that in which the large couplings of the other series are disposed, the pipe-sections coupled with the smaller U-shaped couplings occupying the space formed between the pipes 55 connected by the large U-shaped couplings of the second series, the drain-pipes of the two series being connected to a common exit, and a suitable fan adapted to drive the air beneath the coils through openings formed in 60 the opposite walls of the casing, substantially as set forth.

3. In an air-heating apparatus, a suitable 65 casing, steam-pipes disposed along the inner surfaces of two adjacent or contiguous vertical walls thereof, drain-pipes located below the steam-pipes and disposed along the same contiguous surfaces or walls of the casing, and a series of coils leading from each steam-pipe to its corresponding drain-pipe or that 70 disposed along the same wall, the one series intersecting the other at substantially the angle which the contiguous walls make with each other, the walls of the casing being provided with suitable openings for the admission of air to the system of pipes, substantially as set forth.

In testimony whereof I affix my signature in presence of two witnesses.

HENRY BAETZ.

Witnesses:

EMIL STAREK,
ALFRED A. MATHEY.
